SILHOUETTE CORSELET ENSEMBLE

Filed Jan. 16, 1928

Technical drawing of a woman's garment, likely a corset or girdle, shown from three perspectives. The top row shows a front view (left), a back view (right), and a side view (center). The bottom row shows a front view (left) and a detailed view of the front center (right). The garment features a ribbed, laced-up front with a central panel (part 10). Other labeled parts include 11, 12, 13, 14, 15, 16, 17, 18, 19, 20, 21, 22, 23, 24, 25, 26, 27, 28, 29, 30, 31, 32, and 28'. The bottom right corner contains the text 'INVENTOR. ALMA P. MORIARTY BY *Alma P. Moriarty*'.

UNITED STATES PATENT OFFICE.

ALMA PECK MORIARTY, OF LOS ANGELES, CALIFORNIA.

SILHOUETTE CORSELET ENSEMBLE.

Application filed January 16, 1928. Serial No. 247,141.

This invention relates to improvements in corsets.

The general object of this invention is to provide a novel form of undergarment ensemble suit for women which includes a combined corset and brassière.

Another object of this invention is to provide an improved corset so constructed that it will not stretch in one direction.

10 A further object of this invention is to provide a novel pair of bloomers to be worn with my improved corset and brassière.

Further objects and advantages of this invention will be apparent from the following description taken in connection with the accompanying drawing wherein:

Fig. 1 is a three-quarter front view of a woman wearing one of my improved corselets.

20 Fig. 2 is a view similar to Fig. 1 showing the improved bloomers as they are worn over the corselet.

Fig. 3 is a rear view of my corselet and

25 Fig. 4 is a three-quarter front view of the improved corselet showing the garment unfastened.

Referring to the drawings by reference characters I have indicated my improved undergarment generally at 10. This garment 30 which is made of suitable fabric, includes a corselet portion indicated at 11 and a brassière portion indicated at 12. The corselet and brassière are preferably made of a single piece of material.

35 The corselet, which includes a vertical front or stomach section 14 which extends from the bottom of the garment to the brassière portion, when worn comes just below the bust. This front section includes vertically spaced non-stretchable fabric tapes 15 sewed to the garment material and preferably enclosed in a sheared covering for decorative purposes.

40 For ease of manipulation of the limbs, elastic portions 16 are provided adjacent the bottom of the corselet over each thigh. These elastic portions are bordered by a non-stretchable tape 17 which is similar to the tape on the front section, enclosed in 45 sheared coverings for decorative purposes.

To allow access to the garment the brassière is left open from the top center thereof, where it is provided with a fastening member 18, diagonally as indicated at 19 to 50 each corner of the front or stomach section

14, down each side of the front section to a point spaced from the bottom of the corselet indicated at 20 in Fig. 4.

Adjacent each side of the front section 14 where the garment is open, the material is 60 provided with spaced vertical non-stretchable tapes 21 upon each of which fastening members 22 are secured. The fastening members operate with fastening members 23 on the underside of each of the stomach 65 tapes 15 and serve to secure the corselet together. When the garment is fastened together the material of the corselet overlaps the full width of the front section 14 and the garment is held closed by the two vertical rows of fastening members 21 and 23, thus providing a very substantial connection.

Extending around the corselet portion at right angles to the stomach or front section 14 I provide a plurality of spaced non-stretchable tapes 25. These tapes preferably 75 each comprise a single piece of material extending from the tape 21 around the garment to the edge of the front section 14 which borders the opening. The front section is 80 preferably secured to the material over the tapes 25. The tapes 25 at the bottom of the garment up to the height of the elastic members 16 do not extend unbroken clear 85 around the garment, but do extend unbroken from the border tapes 17 of one elastic member to the border tapes of another elastic member.

For supporting the brassière I preferably 90 provide shoulder straps 26. Secured to each of the vertical border tapes 17 of each of the elastic members 16, I preferably provide elastic members 27 which extend beyond the bottom of the garment and are provided at their lower ends with gripping members 28 95 to thus form garters for supporting the hose of the wearer, as clearly shown in Figs. 1 and 2.

Secured adjacent the bottom of the vertical side tapes of the front section 14 I provide extending elastic tapes 27' having gripping members 28' at their lower ends to form garters similar to the extensions 27.

The non-stretchable tapes 25 of the front section 14 retains the body of the wearer in 100 the shape of the corselet without the aid of the usual stiff corset stays. These stays, heretofore used, are not comfortable and do not allow the freedom of movement such as 105 my improved garment. The wearer of my 110

improved garment 10 has the same freedom of movement of the limbs and torso as would ordinarily be the case if the corselet was not worn.

5 In Fig. 2 I have indicated at 30 a pair of improved bloomers which are adapted to be worn over my improved garment 10. These bloomers are preferably made with an elastic waist band 31 and adjacent the bottom of each of the legs I provide a plurality of tapes 32. The tapes 32 extend completely around the legs of the bloomers and are made of non-stretchable material which is secured to the bloomer base material. These 15 tapes 32 fit the legs of the wearer snugly and prevent the legs of the bloomers from crawling up.

A garment of the structure described, while it has the advantageous feature of 20 closely following the form or figure of the wearer, also serves to support the body of the wearer without hindrance or binding during movement and at the same time performs all of the functions desired in corselet and brassière structures.

If desired the vertical rows of fastening members 21 and 23 may be extended to the top of the brassière portion and the tapes 25 (in that case) would also extend to the 30 top.

From the foregoing description it will be apparent that I have provided a novel form of undergarment which is simple in construction and highly efficient in use.

35 Having thus described my invention, I claim:

1. An undergarment comprising a corselet portion and a brassière portion, said corselet and brassière portions being made of a fabric material, said corselet portion being 40 shaped to fit the form of the wearer and including side and rear portions and a front overlapping portion of double thickness, a plurality of spaced non-stretchable tapes ex-

tending around said garment and secured to 45 said fabric material, said tapes extending onto said overlapping portions, and means on said brassière and said corselet to secure the edges of said overlapping portions together.

2. An undergarment comprising a corselet portion and a brassière portion, said corselet and brassière portions being made of a single piece of single thickness base material, reinforcing means on said corselet portion, said 50 reinforcing means including a plurality of spaced strips extending around said corselet portion and a plurality of other strips extending from the bottom of said corselet portion to the juncture of the corselet portion and the brassière portion in the front of 55 said garment, a resilient member inserted in said corselet portion adjacent the bottom of the garment on each side thereof and said resilient members being bound on the sides and top by a non-stretchable tape, said tape engaging certain of said strips.

3. An undergarment comprising a corselet portion and a brassière portion, said corselet and brassière portions being made of a fabric material, said corselet portion including side and rear portions and a front overlapping portion of double thickness, a plurality of spaced non-stretchable horizontal tapes 70 extending around said corselet portion and secured to said fabric material, the overlapping edges of said front piece in said corselet portion being bound by non-stretchable vertical tapes secured to said fabric over said horizontal tapes and extending from the bottom of said corselet portion to the bottom of 75 said brassière portion and means on said brassière portion and said corselet portion to secure the edges of said overlapping portion together.

In testimony whereof, I hereunto affix my signature.

ALMA PECK MORIARTY.
